C. H. GRÜBE,
DRAFTING COMPASSES,
APPLICATION FILED DEC. 11, 1916.

1,279,537.

Patented Sept. 24, 1918.

Inventor:

Carl H. Grube

By Frank C. Curtis
Attorney

UNITED STATES PATENT OFFICE.

CARL H. GRUBE, OF SCHENECTADY, NEW YORK.

DRAFTING-COMPASSES.

1,279,537.

Specification of Letters Patent. Patented Sept. 24, 1918.

Application filed December 11, 1916. Serial No. 136,124.

To all whom it may concern:

Be it known that I, CARL H. GRUBE, a citizen of the German Empire, residing at Schenectady, county of Schenectady, and 5 State of New York, have invented certain new and useful Improvements in Drafting-Compasses, of which the following is a specification.

Reference may be had to the accompanying drawing, and the reference characters marked thereon, which form a part of this specification. Similar characters refer to similar parts in the several figures therein.

The principal object of the invention is 15 to automatically maintain in parallelism under different conditions of adjustment, the outer members of the jointed legs of a drafting compass, or the like.

Another object of the invention is to automatically maintain under different conditions of adjustment the handle of a compass or instrument with its axis bisecting the angle between the legs of the instrument.

25 Figure 1 of the drawings is a view in front elevation of a drafting compass embodying my invention.

Fig. 2 is a view in side elevation of the same.

30 Fig. 3 is a view in front elevation of one of the outer leg-members detached.

Fig. 4 is a view in perspective of one of the nut-members detached.

Referring to the drawings wherein the 35 invention is shown in preferred form, the instrument has a pair of jointed legs flexibly connected at 1 as by a pivotal connection, each leg comprising an inner member, 2, and an outer member, 3. Each outer leg-member, 3, is pivotally mounted at 4, upon its respective inner leg-member and has an angularly or laterally projecting arm, 5.

40 A pair of nuts, 6-6, are pivotally mounted at 7, upon the respective inner leg-members, one of said nuts being right-hand-threaded and the other left-hand-threaded.

Each of said nuts has a laterally projecting arm, 8, said arms being connected by links, 9, with the respective angularly projecting arms, 5, on the outer leg-members, 3.

45 A right-and-left-hand-threaded adjusting screw, 10, engages both nuts, 6, serving as a means for contracting or expanding the compass.

50 As the compass is contracted or expanded by means of the adjusting screw, the legs

of the compass change their angular position with relation to the respective nuts, 6, causing a relative rotative movement of the nuts, 6, upon the inner leg-members, 2, which 60 movement is transmitted through the links, 9, to the respective angular arms, 5, on the outer leg-members, causing a rotative movement of the outer leg-members upon their respective pivots, 4, relatively to the inner 65 leg-members.

The angle at which the arms, 5 and 8, project, and the proportions of said arms are such as to maintain the outer leg-members, 3, in substantial parallelism throughout 70 the ordinary range of adjustment of the compass.

I have shown one of the outer leg-members, 3, terminating in a simple point or spur, 11, and the other terminating in a pencil-holder, 12, but it will be understood that the outer leg-members may be formed in any known manner and provided with any known marking means adapting them for drafting or scribing purposes. 80

I have shown the instrument provided with a handle, 13, connected with the legs of the compass by a pair of links, 14, said links being pivotally connected at one end at 15, with the handle, and pivotally connected at their other end at 16, one with one of the inner leg-members and the other with the other inner leg-member.

The pivots, 16, are equi-distant from the axis of the pivot, 1, of the compass-legs, and the pivots, 15, are in a line parallel with a line passing through the pivots, 16, so that as the compass is expanded or contracted the handle, 13, will be maintained with its axis bisecting the angle between the legs of 95 the compass whatever that angle may be.

What I claim as new and desire to secure by Letters Patent is:

1. An instrument of the class described having in combination a pair of flexibly connected jointed legs, the outer member of each leg having a laterally offset arm; an adjusting screw; a pair of screw-engaging members pivotally mounted upon the respective inner leg-members, and each having a laterally offset arm; and link-connections between the laterally offset arms on said screw-engaging members and the respective laterally offset arms on the outer leg-members. 100

2. An instrument of the class described having in combination a pair of flexibly con-

nected jointed legs the outer member of each leg having an angularly projecting arm; a right-hand-threaded nut pivotally mounted on one of the inner leg-members, 5 a left-hand-threaded nut pivotally mounted upon the other inner leg-member; an arm projecting laterally from each of said nuts; a right-and-left-hand-threaded screw engaging the respective nuts; and connections

between the angularly projecting arms on 16 the outer leg-members and the respective laterally projecting arms on said nuts.

In testimony whereof I have hereunto set my hand this ninth day of December, 1916.

CARL H. GRUBE.

Witnesses:

GEORGE H. SMITH,

ERNST C. VERWIEBE.
